TOE STIFFENER

Michele Cuozzo, Lynn, Mass., assignor to United Shoe Machinery Corporation, Borough of Flemington, N. J., a corporation of New Jersey

Application December 23, 1938, Serial No. 247,432

9 Claims. (Cl. 36—8.5)

This invention relates to improvements in toe stiffeners and shoes embodying such stiffeners.

In an effort to increase the flexibility of the foreparts of shoes numerous attempts have been made to eliminate the forepart of the insole or to reduce the thickness of the forepart of the insole to a substantial extent. These efforts have been greatly hampered by the lack of inside lateral support for the shoe upper at the point of attachment of the upper to the shoe bottom, a weakness which frequently causes the upper of the shoe to lose its shape about the forepart after a short period of wear.

For the purpose of preserving the shape of the upper in such shoes, it has been proposed to provide a toe stiffener having rearwardly extending wings which form stiff walls at the sides of the shoe between the upper and the lining. Such stiff walls, however, are objectionable inasmuch as when the shoe is bent in walking, the side walls buckle inwardly and thus press against and pinch the wearer's foot, frequently causing bunions or callouses. In addition, these side walls materially decrease the flexibility of the forepart of the shoe.

It is an object of the present invention to avoid the difficulties above referred to by providing a toe stiffener having outline preserving means adapted to afford adequate inside lateral support for the upper in the ball portion without interfering with the flexibility of the shoe, or causing discomfort to the wearer.

It is a further object of the invention to provide a flexible shoe having a half insole, or an insole with a very thin forepart, which will retain its shape about the forepart even after a long period of wear.

In furtherance of these objects, the invention is directed to a toe stiffener having an integral lasting margin with tabs projecting rearwardly along the bottom of the shoe and extending widthwise from a line inwardly of the edge of the shoe bottom and terminating approximately at the edge of the shoe bottom. In another aspect, these tabs are provided with inwardly turned flaps which furnish additional strength to the tabs in their function as outline preserving means. In still another aspect, the invention provides a flexible shoe incorporating a toe stiffener having rearwardly projecting tabs on its lasting margin, which tabs serve as outline preserving means for the forepart of the shoe and permit the forepart of the insole to be eliminated or greatly reduced in thickness.

The invention will be further described with

reference to the accompanying drawing, in which:

Fig. 1 is a plan view of a group of toe stiffener blanks showing how the tabs may be cut out without substantial waste of material; 5

Fig. 2 is a perspective view of the molded toe stiffener;

Fig. 3 is a perspective view of a modified form of the toe stiffener, showing the tabs with inwardly turned flaps; 10

Fig. 4 illustrates a lasted shoe, a portion of the upper being broken away to show the toe stiffener and lining, and

Fig. 5 illustrates the forepart of a completed shoe, a portion being broken away to show the construction thereof. 15

As illustrated in Fig. 1, the toe stiffener blank 10 is cut from a sheet of stiffener material. The forepart of the blank 10 may be approximately semicircular in shape, as in the ordinary shoe, 20 or it may be made in any shape desirable in view of the particular shoe in which it is to be used. About the margin of the forepart of the blank 10 and integral with it is a lasting margin 12. From the ends of the lasting margin 12, which 25 comprise a part of the straight edge 14 of the blank, project tabs 16 approximately equal in width to the lasting margin 12. As illustrated, these tabs 16 are sufficiently long so that when the stiffener 10 is incorporated in a shoe, they 30 will extend rearwardly along the side of the shoe bottom to a point between the ball line and the break line of the shoe, although the length may be varied as desired.

Considered from a somewhat different point 35 of view, the invention comprises a flat rand 12, the width of which is approximately equal to the lasting margin of the upper of the shoe in which the rand is to be used. The outer edge of the rand 12 has substantially the same contour as 40 does the edge of the forepart of the shoe bottom. On the forward portion of the rand 12 and integral with it is a toe stiffener 10, substantially like that used in the ordinary shoe, which extends up the side and over the toe of the shoe. 45

As shown by the arrangement of the blanks in Fig. 1, little additional expense is entailed in complementing the ordinary blank with these tabs, since they are cut from a portion of the material that would be largely wasted in cutting 50 the ordinary blank.

The material from which the blanks are died out may be a firm, resilient and moldable substance, such as fiberboard. In such case, the blanks are then molded to the form shown in 55

Fig. 2, so as to conform to the shape of the shoe in which they are to be used. The tabs 16 are so shaped that their outer edge contours will coincide with the outer edges of the corresponding parts of the forepart of the shoe bottom. Alternatively, the toe stiffeners may be made from such materials as leather which can be softened by moistening or tempering operations or from materials such as can be softened by the use of a solvent or heat. Toe stiffeners made from such materials, are applied to the last after having first been softened and thereafter they are molded on the last to a shape which will be retained when the material hardens.

15 As a means of giving additional strength to the tabs and thereby increasing their utility as outline preserving means, the blank 10 may be shaped as shown in Fig. 1 with flaps 18 extending from the inner edges of the tabs 16 on the blank 10. In such case, in the process of molding, the flaps 18 are turned inwardly, as shown in Fig. 3, to form a folded edge 19 over which the upper may be lasted. With this folded and somewhat rounded edge, when the upper has been 20 lasted and is being roughed prior to the application of cement for sole attaching, there is less danger that the upper will be weakened at the edge of the shoe bottom because of the tendency of the operator to rotate the shoe during the 25 roughing operation. This rotary motion results in more material being removed at the outer edge of the bottom than at points inwardly of the edge. Consequently if the edge of the member to which the upper is lasted is sharp, there is danger of 30 seriously weakening the shoe at this point. In another aspect, the invention provides a shoe having a half insole 20 which extends from the heel part to a point somewhat forward of the break line.

35 40 To the bottom of the half insole 20 are attached the usual fiber shank reinforcing member 22 and metallic shank stiffener 24. The toe stiffener 10 has a lasting margin 12, on the rearmost edge of which are projecting tabs 16 which extend rearwardly along the margin of the shoe bottom. The ends 26 of the tabs 16 overlap the forward edge of the innersole 20 and may be fastened thereto by staples or cement. The tabs, which follow the outline of the shoe bottom and 45 form a firm outline preserving means for the forepart of the shoe, provide a lasting surface to which the upper may be attached. In order to provide extra strength for the outline preserving means a toe stiffener of the type illustrated in 50 Figs. 3 and 4 may be used. In this latter embodiment of the invention, inwardly folded flaps 18 are provided on the outer edges of the tabs, thereby doubling the strength of the tabs. Obviously the flaps 18 may be folded downwardly 55 so as to be between the tabs 16 and the outsole 28 or upwardly so as to be between the tabs 16 and the lining 30. The toe stiffener 10 is usually located between the lining 30 and the upper 32 but it may be inside the lining 30.

60 65 It may be found desirable to make the toe stiffener of some material that can be softened by the use of heat or of some solvent. Frequently this type of material is sticky when soft. If this is the case, the adhesive in the material may be used to hold the lining 30 and the upper 32 together in lasted position, or it may be supplemented by other securing means. The remainder of the shoe may be lasted in any manner desired, such as by staples 34, or tacks 36. The 70 75

attaching means for the outsole 28 is preferably cement.

If desired, instead of employing a half insole 20, a full-length insole may be used, thus avoiding the necessity of employing a sock lining. If a full insole is used, it may be quite thin in the forepart, since the forepart is not needed to support or strengthen the shoe in any way.

It will be obvious to anyone skilled in the art that the use of the toe stiffener herein described is not confined to shoes having half insoles but may be incorporated to advantage in any shoe in which a toe stiffener is employed.

Having thus described my invention, what I claim as new and desire to secure by Letters Patent of the United States is:

1. In a shoe, a molded toe stiffener having an integral lasting margin, said lasting margin having flat tabs projecting rearwardly beyond the side walls of said stiffener, extending widthwise from a line inwardly of the edge of the shoe bottom and terminating in free edges located approximately at the edge of the shoe bottom.

2. In a shoe, a molded toe stiffener having an integral lasting margin, said lasting margin having flat tabs projecting rearwardly beyond the side walls of said stiffener, extending widthwise from a line inwardly of the edge of the shoe bottom and terminating in free edges located approximately at the edge of the shoe bottom, 30 said tabs having inwardly turned flaps along their outer edges.

3. In a shoe, a forepart supporting member comprising a flat forepart rand extending about the edge of the forepart of the shoe bottom and substantially equal in width to the lasting margin of the shoe, the outer edge of said rand being coterminous with said edge of the forepart of the shoe bottom, and a toe stiffener integral with the forward portion of said rand.

4. A toe-stiffener blank having an integral lasting margin and having at one end of its rear edge an integral tab extending rearwardly from said lasting margin approximately equal in width to the lasting margin of the main body of the 45 toe stiffener.

5. A toe-stiffener blank having an integral lasting margin and having at both ends of its rear edge integral tabs extending rearwardly from said lasting margin approximately equal in width to the lasting margin of the toe stiffener.

6. A toe-stiffener blank having an integral lasting margin and having at one end of its rear edge an integral rearwardly extending tab which is substantially a continuation of and equal in 55 width to the lasting margin of the main body of the toe-stiffener blank, said tab having a flap on its inner edge.

7. A flexible shoe comprising an upper, a shank-reinforcing member, a toe stiffener having an integral lasting margin, said lasting margin having flat tabs projecting rearwardly beyond the side walls of the stiffener, extending widthwise from a line inwardly of the edge of the shoe bottom and terminating in free edges located approximately at the edge of the shoe bottom, and an outsole, the upper being secured in overlasted relation to the shank-reinforcing member, the tabs and the lasting margin of the toe stiffener.

8. A flexible shoe comprising an upper, a shank-reinforcing member, a toe stiffener having an integral lasting margin, said lasting margin having flat rearwardly projecting tabs which extend widthwise from a line inwardly of the edge 75

of the shoe bottom and terminate approximately at the edge of the shoe bottom, said tabs having inwardly folded flaps, and an outsole, the upper being secured in overlasted relation to the shank-reinforcing member and the lasting margin of the toe stiffener.

9. A flexible shoe comprising an upper, a shank-reinforcing member, an innersole, a toe stiffener having an integral lasting margin, said lasting margin having flat tabs projecting rear-

wardly beyond the side walls of said stiffener, extending widthwise from a line inwardly of the edge of the shoe bottom and terminating in free edges located approximately at the edge of the shoe bottom, and an outsole, the upper being secured in overlasted relation to the shank-reinforcing member and the inwardly turned lasting margin of the toe stiffener. 5
